UNITED STATES PATENT OFFICE.

JAMES N. HEALD AND RAY D. HUBBELL, OF WORCESTER, MASSACHUSETTS, ASSIGNEES
TO THE HEALD MACHINE COMPANY, OF WORCESTER, MASSACHUSETTS, A CORPORA-
TION OF MASSACHUSETTS.

GRINDING MACHINE.

Application filed March 31, 1924. Serial No. 703,097.

The present invention relates to grinding machines, and contemplates certain improvements and refinements in the reciprocatory table control mechanism disclosed in the co-pending application of Drake and Guild, Serial No. 685,577, filed January 11, 1924,—the principal object herein being to make the wheel dressing and truing operation in a grinding machine wholly automatic from start to finish, once said operation has been inaugurated by the machine operator. The several features of the invention by which the above and other objects are attained are fully set forth hereinafter, reference being had to the accompanying drawings, in which—

Fig. 1 is a view in side elevation of so much of a grinding machine, here shown as of the internal type, as is necessary to disclose the invention.

Figs. 2, 3 and 4 are sectional views on the lines 2—2, 3—3 and 4—4, respectively, of Fig. 1.

Fig. 5 is an enlarged detail view of a latching mechanism forming part of the invention.

Like reference characters refer to like parts in the different figures.

Referring first to Fig. 1, the invention is here shown, by way of example, in connection with the reciprocatory table or carriage 1 of the grinding machine. In such a machine, either the grinding wheel, or the work to be ground, may be carried by the table 1, the reciprocations of the latter being utilized in either case to produce a relative traversing movement between the grinding wheel and the work. As here shown the table 1 supports and carries a wheel head 2 of ordinary construction, the work supporting head 3 being carried by a bridge 4 which spans the slideways provided by the machine frame for the movement of the table 1. Back and forth movement of said table 1, to cause the rotating grinding wheel 5 to make the required traverse of the rotating work piece 6, may be imparted in any well known manner, as for instance, by the use of the fluid pressure controlling and reversing mechanism that forms the subject matter of the copending application of Heald and Guild, Serial No. 629,882, filed April 4, 1923. Such mechanism, or its equivalent, forms no part of the present invention and a detailed description thereof is therefore

unnecessary; it is sufficient to note, for the purposes of the present application, that the type of drive adopted for the actuation of the table 1, be it hydraulic drive, or gear drive, or any other type, procures the reversal of said table at each end of the latter's working stroke by the use of spaced adjustable table dogs 7 and 8, adapted to alternately engage and move an interposed member 9, whose position controls the direction of table travel.

In the normal operation of the machine, with the grinding wheel 5 in contact with the work piece 6, the table 1 will be reversed at each successive engagement of the member 9 by the dogs 7 and 8, which dogs, obviously, are spaced apart on said table a distance corresponding substantially to the working stroke of the grinding wheel 5, i. e., the length of the hole in the work piece 6. As disclosed in the aforesaid application of Drake and Guild, the dog 8 herein is pivoted at 10 to its carrying block 11, so that its other or striking end can be elevated by any suitable means, at the will of an operator; this elevation causes the dog 8 to clear the top of member 9, and thus prevents, when desired, the reversal of the table 1 which would otherwise and normally take place at its right hand limit of working reciprocity,—the right hand movement being continued so as to withdraw the grinding wheel altogether from the working zone, to permit the hole in the work piece 6 to be sized or plugged, or to permit the removal of said work piece and the introduction of a new work piece. This withdrawal movement preferably takes place at high speed; due to the engagement of a bar 13, attached to block 11, with a roller 14 on an arm 15, in the manner described in the aforesaid copending application of Heald and Guild. The mechanism as so far described forms no part of our present invention, and a further detailed reference thereto is therefore unnecessary.

In order to subject the grinding wheel 5 to the action of a dressing or truing device such as shown at 16, Fig. 1, the carrying block 11 of dog 8, instead of being secured directly to the table 1, as is the case with the block 17 of dog 7, is allowed, under certain conditions, to slide freely longitudinally of said table. Under normal conditions, when the table 1 is making its usual working recipro-

- cations, to traverse the grinding wheel back and forth within the work piece, the block 11 of dog 8 is held in definite spaced relation to a block 18, which latter, the same 5 as the block 17 of dog 7, is adapted to be secured by the usual locking devices 19 in any desired position of adjustment longitudinally of the table 1. This connection between the blocks 11 and 18 is here shown in 10 the form of a latch lever 20, which is pivoted at 21 to the block 18, and which has near its free end a shoulder 22 and a pin 23, said shoulder 22 cooperating normally with an abutment 24 on block 11, to hold said block 15 a predetermined distance away from block 18, and said pin cooperating with the right hand edge of block 11 to limit the distance by which said blocks 18 and 11 can be separated.
- 20 As shown in Fig. 5, the latch member 20, when operative, rests by gravity on the flattened surface of a rocking pin 25, which is loosely journaled in the block 11, and which has a handle 26 that allows the operator to 25 swing it through a limited arc, thereby to raise the latch 20 and thus free the shoulder 22 from the abutment 24. When this is done, the block 11 is no longer rigidly connected with the block 18, but on the contrary, said block 11 is free to slide to the left on table 1 as said table moves to the right; in other words, under these conditions, on the right hand movement of table 1, the dog 8 will bear without effect against member 9, and thus the right hand movement of said table will be prolonged beyond the usual reciprocatory working path, so that the grinding wheel 5 will be carried past the dresser 16. This augmented right hand 30 movement of the table 1 causes the block 11 to slide, relative to said table, to the left, owing to the obstruction which the member 9 imposes against the dog 8; finally the adjusting screw 8' of block 11 is brought up 35 against a projection 27 on block 18, whereupon the solid backing thus afforded for the block 11 enables the dog 8 to shift the member 9. This procures reversal of the table 1, and the left hand movement thus inaugurated is caused to restore the parts automatically to normal position in the following manner:—

A member 28, secured rigidly to the frame of the machine, carries a flat spring 29, to the 55 free end of which is secured an upwardly projecting lug 30, for cooperation with the block 11. In the normal grinding operation of the machine, when the blocks 18 and 11 are positively connected for movement in 60 unison by the latch 20, such lug offers no effective obstruction to the back and forth travel of the block 11 in unison with the table 1, it being obvious that when said block, under these conditions, strikes either 65 bevelled side of said lug, the latter will be

wedged downwardly, the spring 29 yielding sufficiently to allow the block to pass over the lug. However, when the block 11 has been freed from the block 18, as above described, to augment the right hand movement of the table 1, the ensuing reversal of said movement, with the block 11 still free, finds the lug 30 in position to contact with the left hand side of said block, and under these conditions, said lug offers an obstruction sufficient to overcome whatever friction there may be tending to cause the block 11 to move to the left with the table. The block 11 being thus held stationary, while the table 1 and block 18 continue to move to the left, the latch member 20 finally resumes its normal position relative to the block 11, when the pin 23 again engages the right hand edge of said block; this allows the shoulder 22 of the latch member 20 to drop 80 behind the abutment 24, and the parts being thus automatically restored to normal position, the block 11 will move in unison with the block 18 and force the lug 30 out of its way, as above described. It is to be understood that in this operation of dressing the grinding wheel 5, the augmented table movement of limited amplitude takes place at the usual working speed, i. e., without the increase in speed that occurs when the full 85 withdrawal movement of the table is effected. This is because the bar 13 is secured to the block 11, and hence when said block slips to the left as above described in the wheel dressing operation, the bar 13 is prevented 90 from coming into contact with the roller 14.

We claim,

1. In apparatus of the class described, a reciprocatory table, a member shiftable in opposite directions to procure the reversals 105 in the movement of said table, adjustable stops carried by said table for engaging and shifting said member, one of said stops being releasable so as to be movable longitudinally to temporarily increase the travel 110 of said table in one direction, said stop ultimately acting to reverse said table, and means for automatically restoring said stop to normal position.

2. In apparatus of the class described, a reciprocatory table, a member shiftable in opposite directions to procure the reversals in the movement of said table, a pair of stops carried by said table for engaging and shifting said member, a block adjustably secured to said table, one of said stops being adjustably secured to said table and the other being held in spaced relation to said block, means for releasing said last mentioned stop from said block, to permit an 120 increase of table travel in one direction, and means for automatically restoring said last mentioned stop to normal position.

3. In a grinding machine, a table carrying a grinding wheel, and adapted to re- 125

- ciprocate, to traverse the work with said wheel, a dresser for said wheel disposed adjacent the normal reciprocatory path of said wheel, a stop carried by said table to limit the travel of the wheel in the direction of said dresser, an adjustable member on said table, a connection holding said stop in spaced relation to said member, means for disengaging the connection to permit traverse of said wheel by said dresser, and means for automatically restoring the spaced relation and reengaging the connection to again hold said stop and said member in spaced relation.
5. In a grinding machine, a reciprocatory table, a member shiftable in opposite directions to procure the reversals in the movement of said table, a pair of stops carried by said table for engaging and shifting said member in the normal working movements of said table, means for increasing the working traverse of said table by releasing one of said stops from said table, said stop ultimately acting to reverse said table, and 10 means operable by the travel of said table for restoring said stop to normal position.
6. In a grinding machine, a reciprocating table, a shiftable member, a stop carried by said table and operable on said shiftable member to limit the table movement in one direction, means for releasing said stop to increase, by a predetermined amount, the reciprocatory traverse of said table in said direction, means engageable with said stop 15 to bring it to rest, making it effective again on said shiftable member, after the table has moved said predetermined amount, and means operable on the reverse movement of said table to return said stop to normal 20 position.
7. In a grinding machine, a grinding wheel, adjustable means for procuring limited reciprocatory working traverse between said wheel and the work to be ground in the normal operation of said machine, a grinding wheel dresser, means operable without destroying the adjustment of said adjustable means to increase the relative movement, in one direction, between said wheel and said work, thereby to subject said wheel, when desired, to the action of said dresser, and means for automatically reestablishing said limited reciprocatory movement after a single increased relative movement.
8. In a grinding machine, a reciprocating table, a stop carried by said table, latching means normally holding said stop fixed with respect to said table, a fixed member in the path of said stop adapted to yield when said stop is held by said latching means, means for releasing said latching means, said member being then adapted to hold said stop and allow it to move relatively to said table, a second stop fixed to said table to limit relative movement of said first stop along said table, said member being operable upon the reversal of said table, after said relative movement, to hold said first stop stationary until said latching means is again made operative.
9. In a grinding machine, a reciprocating table, having a predetermined reciprocal traverse, a grinding wheel dresser out of contact with said wheel during said normal working traverse of said table, means for temporarily increasing the amplitude of table traverse to subject said wheel to the action of said dresser, and means brought into action after the increased amplitude of table movement for automatically procuring said resumption of normal working table traverse.
10. In a grinding machine, a grinding wheel, means for procuring a predetermined reciprocal working traverse between said wheel and the work to be ground in the normal operation of said machine, a grinding wheel dresser, means for increasing the traverse between said wheel and the work by a predetermined amount in one direction, to subject said wheel to the action of said dresser, and means brought into action after such increased traverse for automatically procuring the resumption of the normal reciprocatory working traverse between said wheel and the work to be ground.
11. In a grinding machine, a grinding wheel, adjustable means for procuring limited reciprocal working traverse between said wheel and the work to be ground in the normal operation of said machine, a grinding wheel dresser, means operable without destroying the adjustment of said adjustable means to increase the relative movement, in one direction, between said wheel and said work, thereby to subject said wheel, when desired, to the action of said dresser, and means for automatically reestablishing said limited reciprocal movement after a single increased relative movement.
12. In a grinding machine, a reciprocatory table, a stop carried by said table, latching means normally holding said stop fixed with respect to said table, a fixed member in the path of said stop adapted to yield when said stop is held by said latching means, means for releasing said latching means, said member being then adapted to hold said stop and allow it to move relatively to said table, a second stop fixed to said table to limit relative movement of said first stop along said table, said member being operable upon the reversal of said table, after said relative movement, to hold said first stop stationary until said latching means is again made operative.

Dated this 29th day of February, 1924.

JAMES N. HEALD.

RAY D. HUBBELL.
